UNITED STATES PATENT OFFICE.

EARL L. MARTIN, OF MIAMI, FLORIDA.

CASEMENT-WINDOW HOLDER.

Application filed July 18, 1924. Serial No. 726,661.

To all whom it may concern:

Be it known that I, EARL LEONARD MARTIN, a citizen of the United States, residing at Miami, county of Dade, State of Florida, have invented a certain new and useful Improvement in Casement-Window Holders, of which the following is a full, clear, and exact description.

My invention relates to casement window holders and has for its object to provide a new and improved folding casement window adjuster. It further has for its object to provide a casement window holder which in folding telescopes so as not to hang down or project full length into the room. It further has for its object to provide a holder of that type, which will lock the window closed or lock it in a plurality of non-closed positions through a screen.

The following is a description of an embodiment of my invention, reference being had to the accompanying drawings, in which—

Figure 1 shows plan views of two casement holders adapted, respectively, to open and close casement windows;

Fig. 2 shows a vertical longitudinal section of one of these holders on the line 2—2, Fig. 1;

Fig. 3 shows a section on the line 3—3, Fig. 1;

Fig. 4 shows an enlarged detail of the end of one of the telescoping members;

Fig. 5 shows a section of the same on the line 5—5, Fig. 4; and

Fig. 6 shows an enlarged horizontal longitudinal section of the holder extended.

Referring more particularly to the drawings 2—2 are casement windows hinged to the sash at 4—4. This sash has a screen strip 6 for supporting a screen 7 and having openings through which the casement holders extend. Each opening is provided with a slide plate 8 which is backed by felt 10 so as to make close engagement with the casement holder preventing the entrance of mosquitoes and the like. The sliding plate 8 is carried by a housing 12 mounted on the rail. This housing carries a vertical anchorage pin 14 with which the rod of the holder makes engagement so as to hold the window closed or non-closed. The rod of the holder is a telescoping rod consisting of three sections 16, 18 and 20 adapted to slide one within the other, so that the parts may telescope as shown in Fig. 2, or may be extended as

in Fig. 6. The member 16 is pivoted to the ears of a plate 22 and a spring 24, one end of which bears against said plate and the other end of which enters within the member 16, and tends to move the rod toward the vertical pin 14. Within the hollow telescoping rod there are two locking detents 26 and 28 which move outward and inward through aligning openings in the ends of the telescoping members. The inner ends of these detents have projections which are guided by plates 29, springs 30 being provided which tend to move the detents outward. These detents are provided with longitudinal openings having inclined bottoms which engage inclined surfaces upon controlling wedges 32—34. These wedges are connected together, and to a spring 36 and an operating handle 38 by cables 40, preferably in the form of ball-link chains which, while strong are not liable to snarl. The inclination of the wedge 32 is greater than the inclination of the wedge 34 so that as the operating member 38 is pulled, the wedge 32 will unlock its detent slightly before the wedge 34 will unlock its detent. The spring 36 retracts the wedges 32 and 34 when the handle 38 is released so as to withdraw them from the detents 26 and 28 and permit those detents to move out so as to engage the openings in the outer telescoping members as shown in Figs. 5 and 6 when the rod is fully extended. The inner member 16 is also provided with a locking hook 42 carried by a spring arm and normally engaging the outer surface of the portion 16. When the rod is collapsed the member 18 is forced behind the hook 42 whose head is so shaped that the hook 42 does not interfere with the collapsing of the rod. The rod is provided with a handle 44 surrounding the operating member 38 which can easily be grasped for opening and closing the casement window.

When the window is closed and the rod is collapsed as shown at the right hand portion of Fig. 1, the hook 42 engages the pin 14, locking the window in that position, the spring 24 moving the rod so as to hold the hook in position. When it is desired to open the window, the handle 44 is first pulled so as to extend the rod. When it is fully extended the detents 26 and 28 are forced outward so as to lock the parts in such a way as to hold the rod in extended position. The rod is then moved sidewise to disengage the hook 42 and then pushed, and

when the window is partially opened a notch 46 formed partially in the detent 28 and partially in the rod is made to engage the pin 14 so as to hold the window fixed, the 5 spring 24 acting to move the rod toward the pin 14 and keep it in engagement therewith. When it is desired to partially open the window at another angle, the notch 48 is brought into engagement with the pin 14. 10 When the window is fully opened the notch 47 is made to engage the vertical pin 14 as shown in Fig. 6. When the window is opened and it is desired to close the same and collapse the rod, the rod is first moved 15 out of engagement with the pin 14 and then pulled until the hook 42 engages said pin; the operating member 38 is then pulled so as to cause the wedge 32 to retract the detent 26; the handle is then pushed so as to 20 cause the member 18 to slide upon the member 16; the operating member is then further pulled so as to cause the wedge 34 to retract its detent 28 and the handle is again pushed so as to cause the member 20 to slide 25 upon the member 18, thus bringing the rod into the position shown at the right of Fig. 1, the hook 42 acting to hold the member 16 during the pushing operations referred to.

In order to prevent relative axial movement of the telescoping members the inner members 16 and 18 have slots 49 in which travel the ends of screws 50 carried by the members 18 and 20.

The operating member is provided with 30 a head 52 which acts as a stop when the member is fully retracted.

The wedges are provided with heads 54 to 35 which the chains 40 are connected, these heads being riveted or otherwise secured to 40 the wedges.

With this construction a very neat, collapsible casement window holder is obtained which not only does not protrude out in the room but does not hang down and which can 45 be operated without danger to the user. It further permits the window to be screwed without interference with the adjuster.

As will be evident to those skilled in the art, my invention permits of various modifications without departing from the spirit thereof or the scope of the appended claims.

What I claim is:

1. A casement window holder comprising a plurality of tubular telescoping sections, 55 means within said tubular sections normally

tending to lock said sections when in extended position, and means partially within said tubular sections movable longitudinally of said holder for withdrawing said locking means when desired so as to permit said sections to telescope. 55

2. A casement window holder comprising a plurality of telescoping sections, means normally tending to lock said sections when in extended position, and means movable longitudinally of said holder for withdrawing said locking means when desired so as to permit said sections to telescope, the casement for said window having an anchorage and said rod having a notch adapted to engage therewith, and a spring normally tending to move said rod toward said anchorage. 70

3. A casement window holder comprising a plurality of telescoping sections, means normally tending to lock said sections when in extended position, and means movable longitudinally of said holder for withdrawing said locking means when desired so as to permit said sections to telescope, the casement for said window having an anchorage and said rod having a notch adapted to engage therewith, and a spring normally tending to move said rod toward said anchorage, the inner member of said rod having a yielding detent adapted to engage said anchorage when said window is in closed position. 55

4. A casement window holder comprising a plurality of telescoping sections, means normally tending to lock said sections when in extended position, and means extending through said rod for withdrawing, and a spring within said rod adapted to retract said withdrawing means. 90

5. In a window casement holder the combination of a plurality of telescoping members, a plurality of detents for holding the sections thereof in extended position, means for normally holding said detents in holding position when said holder is extended, means for withdrawing said detents from holding position, an operating member, flexible connections within said rod connecting said means and said operating member together, and a spring for retracting said withdrawing means when said rod is extended, the means toward the inner end of the rod acting to withdraw its detent prior to the means nearer the outer end of the rod. 100 105

EARL L. MARTIN.
